SPARK PLUG AND METHOD OF MAKING THE SAME

Application filed November 22, 1927, Serial No. 235,066, and in Germany November 22, 1926.

This invention relates to the production of spark plugs, and has for its object to improve the quality of such plugs as regards their efficiency and durability. This object is obtained by filling the space between the insulator and the body of the plug by a material in powdered or pulverized form, this material having the qualities of tightening and of conducting the heat, further of equalizing the different degrees of expansion of the insulator and the body of the plug respectively and of fastening the insulator in the plug. This eliminates the disadvantages met hitherto in spark plugs of usual construction which are subject to frequent cracking of the insulator and to rapid wear.

One embodiment of the spark plug is shown by way of example in the accompanying drawing, in which

Fig. 1 is a sectional view of a plug showing the way of applying the method of the invention;

Fig. 2 shows a part of the plug represented in Fig. 1 after the method of the invention has come to an end.

In the embodiment shown in the drawing, 1 represents the usual metallic body (produced by a casting process or otherwise) having a threaded part 2 to be inserted into the cylinder head. 3 indicates an insulator made of porcelain or another material having similar insulating qualities. One electrode or sparking pin is represented by 4, whereas the other electrode is secured to part 2 of the plug. A nut 6 serves for holding the electrical wire. Between the inside surface of part 1 and the outside surface of insulator 3 a space 7 is left. A ring 8 of a soft metal which is able to resist the working temperatures is inserted before the insulator 3 is inserted. The ring 8 rests upon a shoulder formed in part 1 and is pressed against it by edge 9 of the insulator 3. The space 7 is thereby tightly closed against the inner space of threaded portion 2.

Space 7 is filled after insertion of insulator 3 by a pulverized material 10 having tightening and heat conducting qualities, this material preferably consisting of pulverized metal. By means of a suitable tool 11 this

material is pressed rather strongly into the space 7, so that this may be filled by a dense mass. This mass touches all parts of the outer surface of insulator 3 as well as of the inner surface of plug 1 and fills the space 7 in such a manner that irregularities of the formation of said surface which may exist are equalized so that everywhere a good heat conductivity and a tight fit is obtained. Filled space 7 may be made tight to the outside by providing a rim 12 or the like which is bent over in the manner shown in Fig. 2 for closing purposes. A loose metallic ring may, however, be used instead of rim 12.

The difficulty to be overcome in the art of making spark plugs resides chiefly in the difference of rates of expansion due to heat influence between the insulator and the metallic body. The thermal rate of expansion of the insulator being much lower than that of the metallic plug body it is a necessity to carry away the heat from the insulator as quickly as possible which heat would otherwise be stored in it, and would give rise to crackings. It, therefore, is a known fact that the layer 10 provided in space 7 between insulator and body must be of high heat conductivity. This layer must further be of such quality that for all forthcoming temperatures it fills out space 7 in such a manner that insulator 3 is fastened and held tight under all circumstances so that no gas may escape from the cylinder. These conditions may not fully be complied with by existing constructions of spark plugs. They are, however, complied with by a spark plug made in accordance with the invention.

By taking a powdered or pulverized material, preferably a metal or a mixture of metals for filling out space 7, it becomes possible to choose such material as regards its rate of expansion in such a manner that the layer 10 in space 7 is, so to speak, able to equalize the different rates of expansion of the insulator and of the metallic body respectively. The layer 10 (if made of pulverized material having the right rate of expansion) is expanded by the heat of the working temperatures in such a manner as to fully fill out the space 7 (which would be greater for

higher temperatures than for lower ones) without danger of loosening the insulator in its seat or of giving rise to gas leakage. This is due to the structure of the pulverized material and may not be attained by methods known hitherto. The pulverized state of the material 10 brought into space 7 further has the result that all inequalities are equalized and all cavities or holes are filled out which might happen to be present on the outer surface of the insulator 3 and/or on the inner surface of body 1. This is a further important feature resulting in a tight fit of the insulator under all working conditions. 15 By using a pulverized material having the explained qualities it is moreover impossible that the insulator is subjected to sudden strains or stresses giving rise to crackings. The method of the invention results, therefore, in a lowering of the cost to be spent for 20 spark plugs. One of the reasons for this is that the insulator need not be shaped with such exactness as otherwise necessary because its surface need not be as smooth as otherwise 25 and its cross section may slightly differ from a circular one. Further the spark plug will work always and will not give cause to pre-ignitions.

The material 10 preferably is brought into space 7 under pressure which might be exerted by a tool 11 shown in the drawing. It is further of advantage to use the material 10 in as dry a state as possible so that the insulator (which may consist of hygroscopic 35 material) may not draw in humidity from it.

It is necessary to provide means for closing the space 7 against the inner space of portion 2 that is against the cylinder. This is done in the drawing by ring 8 which is pressed 40 tightly against its seat by the insulator 3. It further is advantageous to use other means such as rim 12 shown in the drawing for closing space 7 against the outside.

Aluminium, copper or another metal or 45 alloy may be used as the material 10 or as part of it.

Having described my invention, what I claim as new and desire to secure by Letters Patent of the United States is:

50 1. In a spark plug having a hollow metal body and an insulating body disposed therein, a pulverized metal-containing packing between said metal body and said insulating bodies, said packing being a good conductor 55 of heat and having a coefficient of expansion adapted to vary its volume directly as the volume of the space it occupies varies with the operating temperature range.

2. A spark plug having an insulating body 60 disposed within a hollow metal body, and a layer of pulverized metal-containing material between said metal body and said insulating body, said pulverized layer being a good conductor of heat and having a coefficient of expansion capable of equalizing

the different rates of expansion of the insulating body and of the hollow metal body.

3. A spark plug comprising a hollow metal body having an enlarged tapered opening at one end, a shoulder at the end of said tapered opening, a soft metallic ring on said shoulder, a tapered insulating body disposed in the aforesaid opening and resting on the metallic ring, and a pulverized layer of metal-containing material separating the sides of the insulating body and the enlarged opening, said pulverized layer being a good conductor of heat and having a coefficient of expansion capable of equalizing the rates of expansion of the insulating body and of the hollow metal body so as to always fill the space between the aforesaid bodies.
